His Attorney.

UNITED STATES PATENT OFFICE.

ADOLF FEHSE, OF BERLIN, GERMANY, ASSIGNOR TO GENERAL ELECTRIC COMPANY, A CORPORATION OF NEW YORK.

METHOD OF AND APPARATUS FOR MAKING CONCENTRATED FILAMENTS.

Application filed May 7, 1927, Serial No. 189,506, and in Germany July 10, 1926.

In electric incandescent lamps for certain uses, such as projection, it is frequently desirable that the light source be very concentrated or compact.

5 The degree of concentration of the filament is limited because a lighted filament, especially when at the high temperature attained in gas-filled lamps, becomes somewhat distorted. Even slight distortion may cause 10 danger of contact and short circuits between adjacent parts of the filament, particularly where the filament consists of short close coils side by side. This danger is not fully eliminated, even when the filament is of non-sag 15 tungsten wire and its closely adjacent parts consist of long straight crystals, because a slight distortion, such as a fractional part of a millimeter, may suffice to bring into contact the coils or other parts of the filament which 20 are close together and thus develop a short circuit.

One object of the invention is to provide wire or ribbon filaments which will safely carry heavy currents and which are highly 25 concentrated. Another object is to provide such concentrated filaments which consist of several closely adjacent coils or even of doubly wound coils. To this end the manufacture of the filament is so conducted that a 30 coiled filament of wire or ribbon, or either of them, wound into a helix, is formed over a core which determines the final shape of the filament, and is then clamped with the core in an enclosing box or filament envelope, and 35 therein finally heated so high that the formed filament no longer has any interior stresses and thus is stable and has no tendency to spring or distort. If the filament is of tungsten, the heating of the box and the filament 40 totally enclosed in it is carried to somewhat over 1300° C. In order to bring all parts of the formed filament to as nearly as possible the same temperature the filament is advantageously heated indirectly by heat radiation 45 and not directly by the passage of current through it. To this end the filament envelope and the core are placed in a muffle furnace and left there until both the core and the filament envelope reach the required high 50 temperature. By this invention electric incandescent lamps suitable for projection purposes may be made having filaments with sections very close to one another and doubly coiled into double helices, and may be operated to consume 1000 watts at line voltages of

110 or even 220 volts. Hitherto 1000 watts incandescent lamps with concentrated filaments and suitable for projection purposes could be made only for low voltages, such as 15 to 30 volts.

60 The invention will best be understood in connection with the accompanying drawings, in which is shown one example of a filament made in accordance with this invention and one method of practicing the invention, and in 65 which Fig. 1 is an elevation of a lamp mount having a concentrated filament made in accordance with this invention; Fig. 2 is a cross-section of the filament shown in Fig. 1; Fig. 3 is a view of the filament before it is shaped; Fig. 4 is a side view of the core with a part 70 of the filament in place on it; Fig. 5 is a top view of Fig. 4; Fig. 6 is an end view of Fig. 4; Fig. 7 is a cross-section of the filament heating box containing the formed filament on 75 the core; and Fig. 8 is a longitudinal section through Fig. 7.

76 As one example of the invention the manufacture of a filament suitable for projection purposes and of the form shown in elevation 80 in Fig. 1 and in plan in Fig. 2 will be described. This particular filament consists of six parallel columns or straight sections very close together and made of tungsten wire *a* coiled once or even twice into a helix. The 85 two straight end portions *b* of the helically coiled filament are fastened to leads *c* which are connected to leading-in wires *d*. The bends *e* between the six columns or filament sections are suspended in anchors *f*. Both the 90 anchors *f* and the leads *c* are supported by and sealed into the stem *g*.

95 The manufacture of this filament shown in Figs. 1 and 2 begins with the double coiled straight filament shown in Fig. 3 on a larger 100 scale. The double coiled sections *a* of the filament form in the finished filament the columns or closely adjoining sections, and the single coiled sections *e* form the upper and the lower bends of the filament. The ends *b* of the 105 coiled filament are used, as shown by Fig. 1, as connections to the leads *c*. This coiled filament, made on the usual wire coiling machine, is first shaped by being placed on the core shown on an enlarged scale in three different 110 views in Figs. 4 to 6. The core is an oblong rectangular block *h* of refractory material, advantageously tungsten, provided on both sides with grooves *i* to receive the closely coiled sections of the coiled filament. In the

upper edge of the block *h* are two grooves *k* to receive the two coiled ends *b* which are to be fastened to the leads *c*. The bends *e* of the coiled filament extend along the upper 5 and the lower edges of the block. In order that these bends may also be set in their positions, correspondingly smaller grooves *m* are provided in the upper and lower edges of the block *h* for joining the adjacent ends of the 10 grooves 1 for the straight sections *a* of the filament. Placing the coiled filament in the grooves of the core accurately determines the final shape of the filament.

The filament wound on the core is then laid 15 on the bottom of a boat or trough *n*, Figs. 7, 8 and 9, which also consists of a refractory material, preferably tungsten. Over the wound core *h* there is placed a cup or core *o* which fits over the wound core snugly enough to prevent 20 movement of the filament in the grooves and also fills the boat *n*. This cover likewise consists of a refractory material, preferably tungsten. The cover is pressed down onto the boat by a pin bolt *p* to fit tightly over 25 the wound core *h*. The filament on its core is thus clamped in the filament envelope formed by the boat and the cover and held immovably in place. The boat with the enclosed core clamped in it is then put into a furnace, such 30 as a muffle furnace, and left there until the filament is sufficiently heated. After the boat is taken out and cooled the cover *o* can be raised and the filament removed from its core *h*. The shape given it by the core and 35 the cover *o* is retained by it after being put into the lamp and after the lamp has been used.

The core and the cover can be made of any 40 shape in accordance with the desired final shape of the filament.

What I claim as new and desire to secure

by Letters Patent of the United States, is:—

1. Apparatus for shaping a metal filament into a concentrated form comprising a refractory boat, a cup-shaped cover which fits 45 into said boat with its edges on the bottom of the boat, a core which fits into said cover, and a pin cooperating with said boat to press said cover firmly to the bottom of the boat.

2. Apparatus for shaping a coiled metal 50 filament into a concentrated form, comprising an oblong core having parallel grooves on its sides to receive and position straight sections of said coiled filament, and grooves in its edges to join the adjacent ends of said 55 parallel grooves and to receive intermediate portions of said filament and to position them between said straight sections, a cover which fits snugly over said core and holds the filament in place in said grooves, and means for 60 holding said cover in place during heating of said core and cover.

3. Apparatus for shaping a coiled filament into concentrated form comprising an oblong core having on the sides parallel grooves to hold straight coiled sections of the filament snugly side by side, smaller transverse grooves joining the ends of the side grooves to receive the intermediate bends of the filament, and a cover to fit over the core and filament there- 70 on to hold the filament in said grooves.

4. Apparatus for shaping a coiled filament into concentrated form comprising an oblong core having on its sides grooves of a depth no greater than the radius of the turns of the 75 coils and shaped to fit said coils snugly, and a cover to fit over said core and engage the coil in said grooves throughout its length.

In witness whereof, I have hereunto set my hand this 21st day of April 1927.

ADOLF FEHSE.
